(57) **CLAIM**

The ornamental design for a top of a helmet shell, as shown and described.

DESCRIPTION

FIG. 1 is a perspective view of the design for the top of a helmet shell;

FIG. 2 is a front view of a design for the top of the helmet shell of FIG. 1;

FIG. 3 is a back view of a design for the top of the helmet shell of FIG. 1;

FIG. 4 is a right hand view of a design for the top of the helmet shell of FIG. 1;

FIG. 5 is a left hand view of a design for the top of the helmet shell of FIG. 1;

FIG. 6 is a top view of a design for the top of the helmet shell of FIGS. 1; and

FIG. 7 is a bottom view of a design for the top of the helmet shell of FIG. 1.

FIG. 8 is a perspective view of another embodiment of a design for the top of a helmet shell;

FIG. 9 is a front view of a design for the top of the helmet shell of FIG. 8;

FIG. 10 is a back view of a design for the top of the helmet shell of FIG. 8;

FIG. 11 is a right hand view of a design for the top of the helmet shell of FIG. 8;

FIG. 12 is a left hand view of a design for the top of the helmet shell of FIG. 8;

FIG. 13 is a top view of a design for the top of the helmet shell of FIG. 8; and,

FIG. 14 is a bottom view of a design for the top of the helmet shell of FIG. 8.

In these drawings, the solid lines illustrate the claimed ornamental design, whereas the broken lines illustrate environmental features that form no part of the claimed ornamental design.
